US00D737778S

(12) **United States Design Patent**
Druscovich et al.

(10) **Patent No.:** **US D737,778 S**
(45) **Date of Patent:** **** Sep. 1, 2015**

(54) **CONNECTIVITY MODULE**

(71) Applicant: **Telit Communications S.p.A.**, Sgonico (IT)

(72) Inventors: **Fabrizio Druscovich**, Dolina (IT); **Miran Locatelli**, Dolina (IT); **Cristian Vacchiano**, Buja (IT); **Antonino Sgroi**, Duino Aurisina (IT); **Bruno Vittori**, Sagrado (IT); **Sehoon Park**, Seoul (KR)

(73) Assignee: **TELIT COMMUNICATIONS S.P.A.**, Sgonico (Trieste) (IT)

(**) Term: **14 Years**

(21) Appl. No.: **29/479,418**

(22) Filed: **Jan. 15, 2014**

(51) LOC (10) Cl. **13-03**

(52) U.S. Cl.

USPC **D13/147**

(58) **Field of Classification Search**

USPC D13/147, 154, 184, 199
See application file for complete search history.

(57) **CLAIM**

The ornamental design for a connectivity module, as shown and described.

DESCRIPTION

FIG. 1 is a top plan view of a connectivity module showing our new design;

FIG. 2 is a bottom plan view thereof;

FIG. 3 is a left side elevation view thereof;

FIG. 4 is a right side elevation view thereof;

FIG. 5 is a front elevation view thereof;

FIG. 6 is a rear elevation view thereof; and,

FIG. 7 is a top perspective view thereof.

In the drawing, the even-broken line represents unclaimed environment and forms no part of the claimed design. The dash-dot line represents the boundary of the claimed design.
